MAURICE LACHMAN, OF NEW YORK, N. Y., ASSIGNOR TO LACHMAN MANUFACTURING COMPANY, OF NEW YORK, N. Y., A CORPORATION OF DELAWARE.

KNOCKDOWN BARREL.

1,202,858.

Specification of Letters Patent.

Patented Oct. 31, 1916.

Application filed April 12, 1913. Serial No. 760,593.

To all whom it may concern:

Be it known that I, MAURICE LACHMAN, a citizen of the United States, and a resident of New York, in the county of New York and State of New York, have invented certain new and useful Improvements in Knockdown Barrels, of which the following is a specification.

This invention relates to shipping receptacles or containers particularly of the knockdown type.

The object of the invention is to provide a knockdown container having a metal exterior or interior or both, and, while maintaining all the advantages, the disadvantages and objections such as weight, cost &c. of an all metal receptacle are overcome.

I am aware that knockdown receptacles comprising a plurality of metal sections provided with means for joining them together have been heretofore proposed, but in these types the parts have been made of sections of solid metal so that if sufficient rigidity is given to the metal it becomes so heavy that the weight proposition as well as the cost of material so increases the cost of the receptacle that it cannot be commercially used in competition with a wooden receptacle. Owing to the increasing scarcity of wood, a substitute for this material becomes urgent and metal immediately comes to the foreground, but for a number of reasons, some of which are referred to above, all metal receptacles have not up to the present met with much success.

According to this invention, the body or main part of the container comprises paper, strawboard or similar non-metallic material to give the necessary strength and rigidity to the container, the surface of the paper being coated with a very thin layer or sheet of metal which is adhered thereto over the whole meeting surfaces so as to become practically an integral part of the paper. An extremely thin sheet of metal is all that is necessary, in fact so thin that it merely amounts practically to a coating of metal on the paper surface, yet the coating is of sufficient strength to protect the paper. By

this construction the weight is kept low and the desired strength is maintained while any objections which might be raised against having exposed paper surfaces are avoided.

The invention is primarily designed for knockdown barrels, kegs and similar forms of receptacles and relates to the novel construction of stave or section as well as to the construction of the container as a whole.

The invention consists of the novel parts, combinations of parts and details of construction hereinafter more particularly described and then specified in the claims.

In the accompanying drawings, Figure 1 is a vertical section through a container embodying the present invention. Fig. 2 is a horizontal section through the same taken on the line 2-2 Fig. 1. Fig. 3 is a fragmentary horizontal section through a modification. Fig. 4 is a fragmentary vertical section taken on the line 4-4 of Fig. 3. Fig. 5 is a fragmentary view showing a further modification. Fig. 6 is a perspective view of the preferred form of stay member employed in the construction.

The body portion of the container comprises a plurality of duplicate longitudinal sections which when joined together form a cylindrical body. Each section or stave consists mainly of a panel of paper, strawboard or other similar material 1 formed as a segment of any desired curvature. A preferred manner of forming the paper segments 1 is by first forming a cylinder of a number of layers of paper superimposed on each other, preferably by spinning, and compressed into a very solid mass and built up to any desired thickness. The various layers of paper are united by suitable cement, glue or other adhesive whereby a very rigid wall is attained. After the cylinder has been completely formed, it is severed longitudinally into any desired number of segments 1. By forming the segments in this manner, the segments will retain their conformation and will fit together exactly and form a perfect cylindrical body. The specific manner of forming these segments forms no part of the present invention, this

invention not being limited to any particular manner of forming such part. The paper segment 1 forms the main support and strength giving element of the completed 5 stave.

2 indicates an exceedingly thin metal sheet applied either to the outer or the inner surface of the paper segment 1 or a sheet of metal 2 might be applied to both 10 surfaces as indicated in Figs. 3 and 4. The metal sheet 2 being merely for protection and not relied on for strength, may be of the thinnest metal, 30 or even 40 gage being suitable for the purpose. Said metal 15 sheet is applied under pressure to the surface of the segment 1 so that it forms a protective coating therefor by means of an adhesive preferably consisting of a mixture of silicate of soda and rosin or other resinous compound preferably mixed together in 20 equal quantities and rendered into a plastic or liquid state. The metal sheet is adhered to the paper over the whole surface, in this manner, so that it becomes practically an 25 integral part thereof.

When the metal sheet 2 is applied to the outer surface of the segments as indicated in Figs. 1 and 2, it is preferably provided with flange extensions 3 at the top, bottom 30 and sides, which extensions fold over the edges of the paper segments and bear against the inner surface, whereby protection is afforded for the raw edges of the paper, said paper in this case being inclosed 35 within the metal coating. The paper segments 1 and the metal coatings 2 therefor constitute the stave members of the barrel or keg.

The various staves or sections are joined 40 together by metallic stay members or locking strips of any suitable character, preferably by an I-shaped member formed with two oppositely projecting longitudinal 45 grooves formed by pairs of flanges 4, 5 and 50 in which grooves the longitudinal sides of the staves are seated. The flanges 4 and the web connecting them with the flanges 5 are cut away for a distance from each end forming a shoulder or seat 7 on the stay members 55 and leaving the flanges 5 as an extension 6 from the stay members at each end thereof.

After the staves are all joined together, the heads, one for each end of the body portion, are applied. The heads may be of 55 any suitable construction, the preferred one consisting of a metallic disk 8 provided with strengthening ribs 9 and an annular rim 10 preferably formed into a groove with a depending skirt or flange 11. The ends 60 of the stave members or sections seat in the groove in the rim 10, the flange 11 fitting around the periphery of the sections on the inside of the ends of the stay members as indicated in Fig. 4. The ends 6 of

the stay members are then bent over the rim 65 10 and secure the heads to the body.

12 indicates a paper disk preferably provided on the inner surface of the heads 8, the disk being held in place by the shoulders 7 of the stay members engaging the surface thereof.

If desired, any number of additional hoops 13 may be provided about the periphery of the body and surrounding the 75 stave sections.

A container is thus constructed having an entire metal exterior and which has all the necessary strength of a solid metal one without the weight or high cost of material.

Referring to Fig. 5, the locking members 80 for joining the sections together are provided at one side of each stave section as an integral part of the metal sheet or coating 2. The metal sheet is extended along one side beyond the paper segment 1, doubled back 85 upon itself and formed into a U-shaped groove 14 which engages the edge of the next adjoining section.

What I claim as my invention is:

1. As a new article of manufacture, a 90 rigid heavy paper barrel stave having a sheet of metal adhered to the surface thereof, the edges of said sheet extending around the edges of said stave and terminating on the opposite surface to completely 95 inclose the outer face and both edges of said stave.

2. A knockdown container comprising a plurality of sections adapted to form the body, longitudinal stay members adapted to 100 join said sections to each other, a head for each end of the body having an annular rim in which the ends of the sections are seated, said rim having a depending flange engaging the periphery of said sections, and flexible extensions of said stay members adapted to engage said rim and secure the heads to 105 the body.

3. A knockdown container comprising a 110 plurality of sections adapted to form the body, longitudinal stay members adapted to join said sections to each other, a metallic head for each end of the body having an annular rim in which the ends of the sections are seated, said rim having a depending flange engaging the periphery of said sections inside of said stay members, a paper disk on the inner surface of said head, a shoulder on said stay members adapted to engage and secure said disk in place, and extensions on said stay members adapted to engage said annular rims to secure the heads to 115 the body.

4. A knockdown container comprising a 120 plurality of sections adapted to form a body, longitudinal stay members comprising metallic devices of substantially I cross-sections the width of the webs of which are

substantially the same as the thickness of a section, the bases of said I cross-section stays being extended, securing hooks formed upon said extended portions, a head adapted to be held in position by said hooks and supported upon shoulders formed on said stays, and hoops adapted to secure the said sections and stays together.

Signed at New York, in the county of New York and State of New York, this 10th day of April, A. D. 1913.

MAURICE LACHMAN.
